(57) **CLAIM**

The ornamental design for an aircraft window, as shown and described.

DESCRIPTION

FIG. 1 is an external side view of an embodiment of an aircraft window showing my new design.

FIG. 2 is an external isometric view thereof.

FIG. 3 is an external side view of another embodiment of an aircraft window showing my new design.

FIG. 4 is an external isometric view thereof.

FIG. 5 is an external side view of another embodiment of an aircraft window showing my new design; and,

FIG. 6 is an external isometric view thereof.

Broken lines shown in the drawings illustrate the environment of the aircraft window, and form no part of the claimed design.
